REMINDER SHEETS

Leonard A. Ranko, New York, and Bernard L. Shank,
Flushing, N. Y.

Application February 24, 1954, Serial No. 412,145

1 Claim. (Cl. 116—130)

Our invention is an improved memorandum sheet, especially a sheet having the names of commodities listed thereon, and comprising novel means for indicating which of the commodities so listed must be kept in mind by the user.

An important object of this invention is to provide a sheet of material having projections on its edge, one adjacent each of said names, and an element of elastic material to be attached to any required number of said projections, to prevent all the articles having their names on the sheet adjacent said projections, from escaping the user's attention. The sheet or card is especially intended for the housewife at shopping time to keep her reminded of items to be purchased for the household, such as groceries and other articles for the table and pantry.

The nature and advantages of the invention are fully set forth hereinafter and the novel features are defined in the appended claims. But the disclosure is by way of example only and variations may be adopted in minor respects without omission or marked alteration of any of the essential characteristics.

On the drawings,

Figure 1 is a plan view of a memorandum sheet according to this invention.

The numeral 1 indicates the sheet as a whole. It can be made of cardboard, wood, plastic or other suitable stiff material, and is preferably rectangular in general shape and outline. The shorter opposite edges or ends of the card or sheet have each a pair of apertures 2 with slits 3 connecting the apertures to said edges. A loop 4 of elastic material is disposed in the apertures 2 by slipping it through the cuts 3, so that it lies along one face of the sheet with its ends running across from one aperture 2 to the other at each end of the sheet. Along each of the longer sides are recesses 5, with rounded inner ends 6. The outer ends of the recesses 5 are also rounded off with diverging curved sides to form rounded projections 7 between said recesses 5, and the projections at the ends of each longitudinal row have semicircular notches 8 in line with the edges or ends bearing the apertures 2.

On the card 1 at each projection 7 is a name of a

2

commodity needed by the household of the user, and kept on hand by the grocer or butcher. When there is shopping to be done, the items needed are marked on the sheet by the band 4. For example, if meat is wanted, one side portion 9 of the band is looped into the notch 8, and the recess 5 flanking the projection 7 with the word "Meat" thereon, and similarly with other articles in the list. The sheet 1 and loop 4 can thus serve to indicate one or more articles and the loop acts as a pointer or index member which keeps the buyer informed of everything that must be obtained. As each article is delivered to the buyer, the band is detached from the projection next to the name of said article.

The parts 9 and 10 of the band extending lengthwise between the two rows of projections 7 can lie on the same face as the various names in the two lists, or on the opposite face of the sheet 1, and the parts 9 and 10 can be slipped with equal ease over the projections 7 which indicate the items to be bought. The user then merely scans the projections 7 which are engaged by the portions 9 and 10 of the loop, releasing the projections 7 in succession as the commodities are taken in hand, till the needs of the kitchen and pantry are all filled. The card 1 and loop 4 are preferably in distinctive colors, so that the cook or housewife will not overlook anything that is needed.

The invention is therefore quite simple and inexpensive to produce and at the same time easy to manipulate. The loop 4 is always in position and ready and will remain caught over all the projections 7 that must be included. There are no loose ends to be tied and untied, since the portions 9 and 10 can be slipped over the projections 7, and removed merely by stretching the loop 4.

Having described our invention, what we believe to be new is:

A memorandum sheet of rectangular outline having rows of projections along opposite edges thereof, said sheet having recesses with rounded inner ends and diverging curved sides in said edges to form rows of rounded projections between said recesses, said sheet having the name of an article adjacent each projection, the sheet also having apertures adjacent each end thereof between said rows, and a cut running from each aperture to the adjacent edge of said sheet, and an endless single loop of elastic material having portions in said apertures at both ends and extending from end to end on one face of said sheet, and portions connecting the first-named portions and extending along said rows in position to be engaged with one or more of said projections.
